UNITED STATES PATENT OFFICE

2,492,324

CYCLOTRON OSCILLATOR SYSTEM

Winfield W. Salisbury, Cedar Rapids, Iowa, assignor to Collins Radio Company, Cedar Rapids, Iowa, a corporation of Iowa

Application December 24, 1947, Serial No. 793,680

9 Claims. (Cl. 250—27)

1

This invention relates to orbital electron devices and more particularly to magnetic-electrostatic resonance systems of which the cyclotron system is typical.

A principal object of the invention is to provide a more efficient system employing electron accelerators of the cyclotron type.

Another object is to provide a more efficient cyclotron system which is energized with frequency-modulated high frequency waves.

A further object is to provide a more efficient manner of coupling a high frequency potential source to a cyclotron of the type which is energized by frequency-modulated waves.

A feature of the invention relates to a frequency modulation cyclotron system, wherein the high frequency oscillations are coupled to the dees of the cyclotron by a special coupling arrangement, as a result of which the oscillator tubes and their adjuncts can be located at some convenient place and distance with respect to the cyclotron chamber proper.

Another feature relates to a coupling transmission line between a frequency-modulated oscillator and a cyclotron chamber, whereby the proper phase relations are obtained at the oscillator throughout its frequency-modulated range.

A further feature relates to a frequency-modulated cyclotron system employing grounded grid electron discharge tube oscillators having a feedback loop comprised of symmetrically-connected one-quarter wavelength transmission lines in series with lumped inductances, whereby the delay throughout the feedback loop is maintained substantially uniform over the entire frequency modulation range.

A still further feature relates to the novel organization, arrangement and relative interconnection of parts which cooperate to provide an improved and more efficient cyclotron system.

Other features and advantages not particularly enumerated will be apparent after a consideration of the following detailed description and the appended claims.

In the drawing,

Fig. 1 is a composite schematic and structural diagram of a cyclotron system according to the invention.

Fig. 2 is a detailed view of the cyclotron chamber of Fig. 1.

2

Fig. 3 is a detailed wiring diagram of the oscillator and transmission line coupling system and showing the cyclotron dee electrodes in equivalent analogue form.

5 Fig. 4 is a graph explanatory of the operation of Fig. 3.

Referring to Figs. 1 and 2, there is shown in somewhat schematic form a cyclotron comprising the hollow semi-circular metal dee electrodes 1, 2, which are spaced apart to provide a gap 3 within which is centrally located the electron-emitting cathode 4. The dees 1 and 2 are suitably supported within a closed chamber 5 which can be connected to a vacuum pumping system

15 for maintaining a predetermined vacuum within the chamber. Lead-in wires 6 and 7 for heating the cathode 4 are insulatingly sealed through the chamber wall, and lead-ins 8 and 9 are provided for applying high frequency oscillating potentials

20 respectively to the dees. The peripheral wall of dee 2 has an exit window or slit 10 from which the accelerated electrons or particles emerge and thereafter are deflected by the negatively charged plate 11 so as to follow a path passing through 25 the electron permeable window 12 of the sample bombarding tube 13. Usually the chamber 5 is connected to a source of hydrogen (not shown) at a predetermined pressure.

In the well-known way, the dees are mounted 30 between the opposite pole pieces 14, 15, of a powerful electromagnet so that the interaction between the electrons and the magnetic field causes the electrons to follow a somewhat spiral path, that is one of increasingly greater orbital extent

35 until they emerge from the slit 10. Since the electrons travel over increasing orbital paths around the cathode, if the dees are energized by a single frequency wave, there will, at different portions of gap 3, be lack of synchronism between 40 the wave reversals and the instants when the electrons leave one dee and pass over the gap 3 to the other dee. It has been proposed heretofore to meet this difficulty, by frequency-modulating the high frequency potentials which are

45 applied to the dees. Thus, it has been proposed to bridge the lead-ins 8, 9, within the chamber 5, by a rotating capacitor 16 which rotates at a uniform rate and varies the shunt capacitance across the lead-ins 8, 9, at a regular frequency.

50 This change in capacitance loading of the high

frequency input line feeding the dees, changes the resonant frequency of the supply oscillator 17. Thus the charged particles which follow the orbital paths around cathode 4 are accelerated during that half of the modulation cycle where-in the oscillator frequency is decreasing.

However, one of the difficulties encountered with such frequency-modulated cyclotrons is that of supplying sufficient oscillating energy over the entire modulation range, and the concomitant difficulty of maintaining the phases at the electrodes of the oscillator generator tube in the proper relation for generating sustained frequencies by feedback action. Thus, in one cyclotron arrangement, the oscillator was required to deliver a considerable amount of power in the frequency modulation range between 12 and 25 megacycles per second. This necessarily required oscillator-generator tubes capable of dissipating large powers. Because of this power dissipation requirement, the tubes and their adjuncts necessarily must be physically very large; and because of the configuration of the cyclotron chamber proper it is well nigh impossible to couple the oscillator tubes directly into the resonant dee chamber.

In accordance with one phase of this invention, there is provided a coupling arrangement which will allow the oscillator tubes to be located conveniently at some distance from the dee chamber of the cyclotron. Where the cyclotron is operated at a fixed frequency, as distinguished from frequency modulation, there is no problem in using the transmission lines for coupling, because the phase shift of the transmission line can be controlled by fixing the electrical length so that the over-all phase shift satisfies the requirement for sustained oscillation. However, in the case of a frequency-modulated supply where it is necessary to vary the frequency of the oscillator 17, the problem of maintaining the desired phase shift in the feed back circuit of the oscillator becomes very difficult.

One arrangement that was found to be satisfactory for this purpose is shown in Figs. 1 and 3. In Fig. 3, the dee structure of the cyclotron is represented by the half-wave shorted coaxial transmission line 18, this being possible because the dee structure of a cyclotron forms a high Q resonant tank circuit having distributed constants. In accordance with the invention, the oscillator-generator tube 19 is of the grounded grid type, that is its control grid 20 is substantially at ground potential for the high frequency waves. While the drawing shows a single oscillator tube 19, preferably it consists of four or more such tubes connected in parallel. For purposes of simplicity, only one tube is illustrated in the drawing and its comprises an electron-emitting cathode 21, control grid 20, and plate or output anode 22. The tubes 19 may each be of the type designated 880 by the Radio Manufacturers Association, and capable of delivering a useful output of 45 kilowatts. In that case the plate power supply 23 may have its positive terminal grounded and capable of supplying 10,000 volts negative potential to the cathode 21, at 6 amperes output.

In Fig. 3, the resonant circuit of the cyclotron proper, that is the dee structure, is represented by the half-wave coaxial transmission line 18, which is shorted at its opposite ends and the electrical length of this transmission line being varied by the continuously variable capacitor 16a which is analogous to the capacity 16 of Fig. 1.

Since this dee structure is a high Q resonant tank circuit, the coupling to the oscillator can be taken therefrom adjacent each end thereof so that there is substantially zero phase shift between the voltage at one end of the line 18 as compared with the voltage at the other end of this line 18. For this purpose, the dee structure is provided at each end with lead-in lines 24, 25, each consisting of a coaxial wave transmission line of one-quarter wavelength at the midpoint of the operating range of the frequency modulations, that is at 18 megacycles in the example assumed above. The outer conductors of lines 24, 25, and the resonant chamber 18, are grounded as shown. The center conductor 26 of line 24 is connected in series with the lumped inductance 27 to the anode 22 of the oscillator. Likewise, the center conductor 28 of line 25 is connected through the lumped inductance 29 and thence through the capacitor 30 to the cathode 21.

In Fig. 3, the capacitance C represents the grid-to-anode capacitance of tube 19 plus the stray capacitance of the circuit, and in the particular example mentioned above, equals approximately 177 mmf. Capacitance C1 represents the cathode-to-grid capacitance of the tube 19 and the stray capacitance of the circuit and in the example assumed was equal to 120 mmf. The capacitance 31 is an additional capacitor connected effectively across the grid 20 and cathode 21, and in the example above mentioned, is equal to 885 mmf. The capacitor 32 is a filtering capacitor of .01 mf., which cooperates with the cathode choke coil 33 to isolate the radio frequency energy from the conductors leading to the power supply 23. The capacitor 34 is a by-pass capacitor having a value of .02 mf., to maintain the grid 20 effectively at radio frequency ground potential. The capacitor 30 above described, is a coupling capacitor of .012 mf., and serves to isolate the negative high voltage terminal 35 of the power supply so that it is not short-circuited to ground in the cyclotron dee. The anode inductance 27 may have an inductance of 0.42 microhenry, and the cathode inductance 29 may have a value of 0.0763 microhenry, while inductance 33 may have a value of .5 microhenries. The feedback path for tube 19 is as follows. The high frequency voltages at the anode 22 pass through the inductance 27, coaxial transmission line 24, the cyclotron dees as represented by the half-wave line 18, thence through the one-quarter wave coaxial transmission line 25 and inductance 29 to the cathodes 21 of the oscillator tube. The coaxial transmission lines 24 and 25 are adjusted to be one-quarter wavelength long at 18 megacycles, which in the assumed example is the midpoint of the operating frequency-modulated range of the oscillator.

In order that the grounded grid oscillator 19 can operate properly, it is necessary that the cathode and anode circuits operate with their voltages close to and in-phase relationship. Since at 18 megacycles there is approximately 90° phase shift across each of the lines 24, 25, it is necessary to provide an additional 180° phase shift so as to maintain the in-phase relationship between the cathode and anode circuits. This is made possible through the delays provided by the lumped inductance 27 and the shunt capacitance C in the anode circuit and by the lumped inductance 29 and the combined capacitances C1 and 30 in the cathode circuit. By the proper selection of the values of inductances 27, 29, and capacitance 30, it is possible to maintain sub-

stantially 360° shift throughout the range of 12 to 27 megacycles as is illustrated in the graph of Fig. 4. Following is a chart of specific values for the phase delays involved for both 18 and 25 megacycles.

Summary of phase calculations

18 mc.:

Delay in lumped anode net (27, C)	77.5°
Delay in output line 24	90.0°
Dee lags anode 22 by	167.5°
Delay in cyclotron	Zero
Delay in feedback line 25	90.0°
Delay in lumped cathode net (29+30)	77.5°
Cathode lags dee by	167.5°

Hence cathode lags anode by 335.0°
or cathode leads anode by 25.0°

25 mc.:

Delay in lumped anode net (27, C)	173.8°
Delay in output line 24	5.6°
Dee lags anode 22 by	179.4°
Delay in cyclotron	Zero
Delay in feedback line 25	5.0°
Delay in cathode lumped net (29+30)	173.8°
Cathode lags dee by	178.8°

Hence cathode lags anode by 358.2°
or cathode leads anode by 1.8°

It can be seen from the above tabulation and the graph of Fig. 4, that the sum of the phase delays of the coupling transmission lines 24, 25, and the lumped networks consisting of inductance 27 and the capacitance C on the one hand, and inductance 29 and the capacitance 30 on the other hand, is substantially 180° throughout the entire range of 12 to $27\frac{1}{2}$ megacycles. The circuit as described and as disclosed in the drawing, therefore, provides a convenient method by which a high powered electronic tube oscillation generator can be coupled to a cyclotron which is to be energized with frequency-modulated high frequency waves over a wide range of modulation.

While one particular embodiment has been illustrated, various changes and modifications may be made therein without departing from the spirit and scope of the invention.

What is claimed is:

1. A system for producing high velocity electrons traveling in orbital paths of increasing radius, comprising a pair of electrodes for accelerating electrons in resonance with applied high frequency waves, electron discharge tube oscillator means for exciting said electrodes, means to vary the capacitance across said electrodes and thereby to vary the frequency of the oscillator in timed correlation with the increase in said orbital path radius, and a feedback circuit for said oscillator comprising a first transmission line and an inductance in series therewith and connected to the anode of said oscillator, a second wave transmission line and an inductance in series therewith and connected to the cathode of said oscillator, said transmission lines being symmetrically connected to said electrodes, each of said transmission lines being a one-quarter wave line at the midpoint of the operating fre-

quency range of said oscillator, said inductances and transmission lines being proportioned to maintain the excitation of said anode and cathode in substantially like phase and substantially regardless of the frequency of said oscillator.

2. A cyclotron system comprising a pair of cyclotron electrodes for accelerating electrons in orbital paths of increasing radius and in resonance with applied high frequency waves, electron discharge tube oscillator means for exciting said electrodes, means to vary the effective capacitance across said electrodes and thereby to vary the frequency of the oscillator in timed correlation with the increase in said orbital path radius, a feedback path connected between the anode of the oscillator and one of said electrodes and including a lumped inductance and a coaxial wave transmission line section, another feedback path connected between the cathode of said oscillator and the other of said electrodes and including a lumped inductance and a coaxial wave transmission line section, each of said coaxial transmission line sections being a one-quarter wave line at the midpoint of the operating frequency range of said oscillator.

3. A cyclotron system comprising a pair of cyclotron electrodes for accelerating electrons in orbital paths of increasing radius and in resonance with applied high frequency waves, electron discharge tube oscillator means for exciting said electrodes, said oscillator having means to maintain its control grid at substantially ground potential for high frequency waves, a feedback path from the anode of the oscillator to one of said electrodes, a feedback path from the cathode of the oscillator to the other of said electrodes, each path including a lumped inductance in series with a coaxial wave transmission line, each transmission line being of one-quarter wavelength at the midpoint of the operating range of said oscillator, and means to vary the effective capacitance across said electrodes to vary the operating frequency of said oscillator between predetermined limits and in timed correlation with the said increase in said orbital path radius.

4. In combination, an evacuated device having an electron emitter and a pair of electron accelerating electrodes, at least one high frequency oscillator-generator tube for exciting said electrodes for progressively and cumulatively accelerating the electrons from said emitter in trajectories of increasing electron transit time, means to frequency-modulate the oscillations from said generator in timed correlation with the increase in the electron transit time of said trajectories, said device having the electrical characteristics equivalent to a coaxial wave transmission line which is of one-half wavelength and short-circuited at opposite ends, a one-quarter wave coaxial transmission line connecting one of said electrodes to the anode of said oscillator tube, another one-quarter wave coaxial transmission line connecting the other electrode to the cathode of said oscillator tube, and lumped reactances connected in circuit with each of said one-quarter wave transmission lines to maintain the anode and cathode of said oscillator tube in substantially like phase with respect to the generated oscillations and substantially independent of the frequency of said frequency-modulated oscillations.

5. In combination, an evacuated device having an electron emitter and a pair of electron accelerating electrodes, at least one high frequency oscillator-generator tube for exciting said elec-

trodes to progressively and cumulatively accelerate the electrons in trajectories of increasing electron transit time, said device having the electrical characteristics equivalent to a high Q resonant cavity, means to frequency-modulate the oscillations from said generator in timed correlation with the said increase of the electron transit time of said trajectories, a one-quarter wave coaxial transmission line connected to one of said electrodes, another one-quarter wave coaxial transmission line connected to the other of said electrodes, a lumped inductance connected between the first coaxial wave transmission line and the anode of said oscillator tube, another lumped inductance connected between the second coaxial transmission line and the cathode of said oscillator tube, and means to maintain the grid of said oscillator tube substantially at ground potential for high frequency waves.

6. The combination according to claim 5 in which a continuously varying capacity is connected across said electrodes to vary the frequency of the oscillator.

7. In combination, a grid controlled electron discharge tube oscillator, means to maintain the control grid of said oscillator at substantially ground potential for high frequency waves, a tank circuit connected across the anode and cathode of said oscillator and including a variable loading capacitor, said tank circuit constituting a resonant cavity short-circuited at opposite ends, a one-quarter wave transmission line connected adjacent one end of the cavity and in series with an inductance to the anode of said tube, and a one-quarter wave transmission line connected adjacent the opposite end of said cavity and in

series with an inductance to the cathode of said oscillator tube, and means to vary the resonant frequency of said cavity and thereby to vary the frequency of the oscillator tube while maintaining the excitation of the anode and cathode of said oscillator in substantially like phase.

8. The combination according to claim 6 in which said inductances are proportioned with respect to the said one-quarter wave lines to maintain the anode and cathode of said oscillator tube in proper feedback phase over the entire operating frequency range of said oscillator.

9. The combination according to claim 7 in which said resonant cavity is constituted of two cyclotron-dee electrodes.
